UNITED STATES PATENT OFFICE.

WILLIAM H. WHEELER, OF NEW YORK, N. Y.

FIREPROOF DOOR.

1,377,298.

Specification of Letters Patent.

Patented May 10, 1921.

Application filed June 8, 1920. Serial No. 387,405.

To all whom it may concern:

Be it known that I, WILLIAM H. WHEELER, a citizen of the United States, and resident of New York, in the county and State of 5 New York, have invented certain new and useful Improvements in Fireproof Doors, of which the following is a specification.

This invention relates to fireproof doors of that class in which the structure employs 10 a fireproof composition material inclosed within a metallic surface sheathing, and it has for its object to provide an improved fireproof door of this character which will afford advantages especially in respect to 15 lightness and strength, facility and economy in manufacture, simplicity and inexpensiveness in construction, and the maximum of effectiveness and general efficiency in use.

In the drawings—

20 Figure 1 is a face view of a portion of a door embodying my improvements, partly broken away to show the interior construction.

25 Fig. 2 is a detail horizontal cross-section, on the line $x-x$, Fig. 1.

Fig. 3 is a detail vertical cross-section, on the line $y-y$, Fig. 2.

Fig. 4 is a detail vertical cross-section, on the line $z-z$, Fig. 2.

30 Corresponding parts in all the figures are denoted by the same reference characters.

Referring to the drawings, 1 designates a panel sheet, which constitutes the main portion of the door and which is formed of a 35 rigid non-metallic composition of low heat conductivity and of fireproof quality, for which purpose I prefer to use the composition which is commercially known as "alignum" and is substantially undeformable by 40 heat and which is constituted by a suitable filler including asbestos and combined with a fireproof binder to produce a plastic substance which is molded into shape and compressed and dried in a rigid structure.

45 The panel sheet 1 is preferably formed of two layers of the fireproof composition, though it may be formed of a single solid mass thereof, and its entire side surfaces are covered by a metallic sheathing preferably 50 consisting of steel sheets, 2-2, secured to the face of the composition panel body. The surface sheathing is in practice secured to the composition panel body at all points of its face area, the preferred method being 55 by cementing the steel sheets to the panel

body, whereby the metallic sheathing is effectively bonded to the composition body in such manner as to preclude possibility of rusting or corrosion of the steel by damp intervening air spaces, and also eliminating 60 a metallic ring in the door structure or a "wavy" appearance of the surface sheathing, and affording a greater strength and stiffness than if the steel sheets were simply laid on the composition panel body and se- 65 cured thereto at separate points.

It will be noted that the panel sheet with its metallic surface sheathing extends to the very edge of the door structure, whereby enhanced strength and resistance to strains is 70 effected.

The edge of the body panel 1 is surrounded by a frame, at the edge of the door, which is formed by bars or stiles, 3-3, respectively placed against the faces of the edge 75 portion of the panel body, which bars or stiles are of suitable thickness and are formed of a rigid non-metallic composition corresponding to that of the panel sheet. Said bars of the edge frame or structure are 80 preferably covered by a metallic sheathing, as at 4, preferably consisting of a steel plate which extends over the surface of the bar or stile except at its inner face, which metallic plates are preferably locked into the 85 composition body of the bar by a turned or angular edge, as at 5, which enters the composition body during the process of forming and compressing the same into shape, but this metallic sheathing for the bars or 90 stiles is not an essential feature of the structure and is employed under preferred conditions as an additional medium for enhancement of strength and resistance to 95 strains.

The bars or stiles 3-3 extend longitudinally at the edge of the door, and are mounted in secured connection with the panel body 1 by means of transverse bolts, 6, extending through both stiles and the panel 100 body. The bolts engage nuts, 7, constituted by a rectangular metallic plate countersunk in a corresponding recess in the outer face of the stile 3, said bolt-plates being preferably embedded in the plastic composition 105 body of the stile during the process of molding and compressing the same into shape. The nuts are thus buried within the composition body and are held fast, so that no retention of the nut is necessary in the process 110

of screwing the bolt home into engagement therewith. The bolts have a flat head, 8, corresponding to a screw head, which is countersunk at the outer face of the bar or 5 stile 3 and is flush with the surface thereof. In practice, the metallic sheathing plate 4 is relatively thin and the composition body of the stile is of such a nature that the sheathing plate and composition body can 10 be bent in sufficiently to form the depression in which the head of the bolt is countersunk flush with the surface of the stile, which avoids the necessity of cutting away to provide the essential recess in usual 15 countersunk constructions and also avoids the cutting away of the metallic sheathing and thus conserves the strength afforded by the latter. The bolts and nuts are provided at intervals, preferably in two parallel 20 series which are staggered with relation to each other, as shown.

The whole edge-frame structure, as above described, is covered by a metallic surface sheathing, which preferably consists of a steel sheet, 9, said metallic sheet being preferably thin and being bent around to cover the outer edge face, as at 10, of the frame formed by the bars or stiles 3—3, the side faces thereof, as at 11—11, thus concealing the heads of the bolts and the embedded nuts, and the inner edge faces, as at 12—12, of the frame.

The edge-frame sheathing 9 fits closely in its relationship to the inclosed frame structure, to provide an auxiliary stiffening media for the latter, and when locked in position serves to seal the whole frame structure in its relationship of parts. Said sheathing plate 9 is locked or sealed at its 35 terminal edges at the inner edge-faces of the frame adjacent the panel sheet 1, for which purpose its terminal end edges, 14—14, are turned outwardly and may be soldered or otherwise secured in position. The preferred construction, however, for locking or securing comprises metallic strips 15—15, which may be formed of relatively thin steel plates, inserted between the face of the bars or stiles 3—3 and the metallic-sheathed 40 panel body 1 before the parts are bolted and secured together. Said strips or plates 15—15 have their end edges, 16, projecting at the inner edge-face of the frame structure, and these end edges are bent outwardly 45 and downwardly over the terminal end edges 14—14 of the edge-frame sheathing 9, as at 17—17, to lock and seal the latter in position.

I will now describe a leading feature of 60 my invention with relation to the type of door to which my improvements relate. This feature consists of a metallic strip, 18, preferably steel, in plate form and relatively thick, which extends along the edge of the door and is interposed between the outer

end of the edge-frame and the portion 10 of the edge-frame sheathing 9 which extends at the outer edge face. Said steel strip 18 extends longitudinally of the edge of the door and coincident with the area thereof, 70 and is thus inclosed within the frame sheathing 9 and positionally retained thereby, and its operation is to enhance the stiffness and strength of the door against flexure or strains and to increase the resistance of the 75 edge of the door against accidental blows or other conditions of service or use. The strip 18 thus acts normally as a bracing element, and is not attached rigidly by fastening means to the door structure but is in a 80 sense a "floating" or loose element which is simply retained by its inclosure within the frame sheathing 9, though under some conditions of use its positional status may be enhanced by a single or slight fastening, 85 such as a single screw attaching it to the edge-frame structure, which will not substantially affect its operative function as a 90 "floating" or relatively loose element. The operative floating characteristic of the metallic brace strip 18, as just defined, permits of a high degree of longitudinal expansion of the strip with relation to the comparatively slight expansion of the composition 95 fireproof material of which the frame bars or stiles 3—3 and the panel sheet 1 of the door are formed, under subjection to high temperatures such as would occur in a fire. There is therefore no tendency under the 100 expansion action of the brace and strengthening strip 18 to cause buckling or warping of the main composition structure of the door in a fire, which buckling or warping would decrease the efficiency of the door structure in its resistance against the 105 conditions of a fire and in its office as an effective closure under such conditions. But in its normal service under ordinary conditions of use the floating steel strip operates as an effective brace and stiffening resistance 110 against shocks or strains direct at the edge of the door or laterally at the sides thereof, and thus enhances the strength and rigidity and efficiency of the entire door structure.

Also, under conditions of fire, the expansion of the metallic edge-frame sheathing 9 will not cause the main composition structure of the door to buckle or warp, as this sheathing being of relatively thin gage steel 115 can expand to a greater degree than the composition material without sufficient force to draw upon the latter and cause a buckling or warping thereof, but the thin steel sheet will itself buckle locally in waves.

Under the conditions as above set forth, 125 the integrity and service of the main composition door structure in a fire is therefore not dependent upon either the metallic edge-frame sheathing plate 9 or the metallic brace and stiffening strip 18, but will be 130

unaffected by the expansion of these metallic elements. The enhanced strength and stiffness and resistance afforded by said metallic elements are of service only when the 5 door is in normal conditions of use and liable to shocks or strains or when open. When closed, as is the case with these protective doors during a fire, the composition door structure is supported by the door 10 frame, and under conditions of fire the metallic elements as just referred to are not designed to be operative and are not essential to the integrity and effective service of the door, nor is the latter affected by the 15 high degree of expansion which would then ensue in said metallic elements.

When the inner metallic sheathing plate 4 covering the bars or stiles 3-3 is not employed, this element not being an essential 20 feature of the structure, the improved door is adapted for ready and convenient adjustment to compensate for variations in the door frame or other resultant conditions of use. For instance, the lock or seal at the 25 terminal edges 14-14 of the edge-frame sheathing 9 can be then opened and said sheathing as well as the metallic brace strip 18 removed from position, after which the outer edge of the composition frame can be 30 reduced to limit the size of the door or a strip can be placed at said edge to enlarge the size of the door, and then the metallic brace strip 18 and the edge-frame sheathing 9 can be returned to normal position. In 35 this connection it will be understood that the composition material of which the bars or stiles 3-3 and the panel sheet 1 are formed is readily workable in the same manner as ordinary lumber.

40 The operation and advantages of my invention will be readily understood by those skilled in the art to which it appertains. The structure enables convenient and comparatively inexpensive and rapid manufacture of the door in simple successive steps, and in the described association of the metallic elements affords great strength and rigidity and resistance to all normal conditions of shock or strain in ordinary service or use, 45 and under conditions of fire the expansion of the metallic elements will not affect the integrity of the composition door structure but the latter will effectively serve its office and retain its normal status of resistance 50 without buckling or warping.

Having thus described my invention, I claim and desire to secure by Letters Patent:

1. A fireproof door of the class described, 55 comprising an edge-frame constituted by bars or stiles formed of a rigid non-metallic composition, a relatively-thin metallic plate forming a surface sheathing for said edge-frame, and a relatively-thick metallic strip extending at the outer edge of said frame 60 and positionally retained by said surface

sheathing plate, said strip having a substantially floating or loose status relative to the frame.

2. A fireproof door of the class described, 70 comprising an edge-frame constituted by bars or stiles formed of a rigid non-metallic composition, a relatively-thin metallic plate covering the surface of said edge-frame at its outer face and side faces and inner faces and having its terminal end edges locked or 75 sealed at the inner face of the edge-frame to retain said surface sheathing in position, and a relatively-thick metallic strip inserted between the outer face of the edge-frame and the outer portion of said surface sheathing 80 and extending longitudinally of the edge and positionally retained by said surface sheathing plate in a substantially floating or loose status relative to the frame.

3. A fireproof door of the class described, 85 comprising an edge-frame constituted by bars or stiles formed of a rigid non-metallic composition, a panel or body member likewise formed of a rigid non-metallic composition and inserted between said bars or stiles 90 and secured in connection therewith, a relatively-thin metallic plate forming a surface sheathing covering said edge-frame and having its terminal end edges locked or sealed at the inner faces of the edge-frame to retain 95 said sheathing in position, and a relatively-thick metallic strip inserted between the outer face of said edge-frame and the outer portion of said surface sheathing and positionally retained by said sheathing plate in 100 a substantially floating or loose status relative to the frame.

4. A fireproof door of the class described, 105 comprising an edge-frame constituted by bars or stiles formed of a rigid non-metallic composition, a panel body sheet formed of a rigid non-metallic composition and inserted between said bars or stiles and extending to the outer edge of said frame, means extending transversely through said bars or stiles 110 and the panel sheet to secure said composition elements together, a relatively-thin metallic plate forming a surface sheathing for said edge-frame and covering said securing means, means for fastening or sealing the terminal end edges of said surface sheathing at the inner faces of the edge-frame, and a relatively-thick metallic strip inserted between the outer face of the edge-frame and the outer portion of said surface sheathing 115 and positionally retained by said sheathing in a substantially floating or loose status relative to the frame.

5. A fireproof door of the class described, 120 comprising an edge-frame constituted by bars or stiles formed of a rigid non-metallic composition, a panel or body portion formed of a rigid non-metallic composition and in connection with said edge-frame, means extending transversely through said composi- 125

- tion elements for securing said panel body and said bars or stiles together, a plate extending over and inclosing said composition elements and forming a surface sheathing 5 for said edge-frame, and a metallic strip inserted between the outer face of said edge-frame and the outer portion of said metallic sheathing and positionally retained by said sheathing.
- 10 6. A fireproof door of the class described, comprising an edge-frame constituted by bars or stiles formed of a rigid non-metallic composition, a panel or body member formed of a rigid non-metallic composition and extending within said edge-frame and to the outer face thereof, transverse securing means 15 extending through said composition elements to secure the panel body and bars or stiles together, a metallic plate covering and inclosing said composition elements and fastening means and forming a surface sheathing for the edge-frame, means for locking or sealing the terminal end edges of said sheathing plate at the inner faces of the edge-frame, and a metallic strip inserted 20 between the outer face of the edge-frame and the outer portion of said surface sheathing and positionally retained by said sheathing plate.
- 25 7. A fireproof door of the class described, comprising an edge-frame constituted by

bars or stiles formed of a rigid non-metallic composition, a panel or body member formed of a rigid non-metallic composition and extending within said edge-frame and to the outer face thereof, nut members embedded 35 within the outer face of said bars or stiles, transverse bolts extending through said composition elements and engaging said nut members to secure the bars or stiles and the body panel together, a metallic plate covering and inclosing said composition elements and said securing means and forming a surface sheathing for the edge-frame, and means for locking or sealing the terminal 45 end edges of said metallic sheathing plate in connection with the composition structure.

8. A fireproof door of the class described, comprising a main body and edge structure formed of rigid non-metallic composition 50 elements secured together, a metallic brace strip or plate extending at the outer face of the edge of said composition structure and having a substantially floating or loose status relative thereto, and a metallic sheathing extending over and inclosing said brace strip and positionally secured in connection 55 with said composition structure.

In testimony whereof I have signed the foregoing specification.

WILLIAM H. WHEELER.
